UNITED STATES PATENT OFFICE.

ISAAC STROUSE, OF NEW HAVEN, CONNECTICUT.

DESIGN FOR A CORSET.

SPECIFICATION forming part of Design No. 12,686, dated January 10, 1882.

Application filed December 15, 1881. Term of patent 7 years.

To all whom it may concern:

Be it known that I, ISAAC STROUSE, of New Haven, in the county of New Haven and State of Connecticut, have invented a new Design for 5 Corsets; and I do hereby declare the following, when taken in connection with the accompanying drawing and the letters of reference marked thereon, to be a full, clear, and exact description of the same, and which said drawing constitutes 10 part of this specification, and represents a side view of the hip-section complete.

This invention relates to a design for the ornamentation of that part of a corset commonly called the "hip-section"—that is to say, the 15 part of the corset between the front and back, and which extends from under the arm down over the hip; and the design consists in the representation of cords or ribs in series, as shown in the accompanying illustration and 20 hereinafter described.

Across the center is the representation of a 25 transverse series of ribs, *a*. Midway between that series and the top is the representation of a second transverse series of ribs, *b*, and midway between the center series and the lower edge is the representation of a third transverse series of ribs, *c*. Between the middle series, *a*, and the series *b* above is the 30 representation of a series of ribs, *d*, running diagonally from the upper series downward and

forward to the middle series, leaving a plain space at the front and rear. Between the middle series and the series below is the representation of a series of ribs, *e*, running diagonally downward and backward, leaving a plain space 35 at the front and rear. Above the upper series, *b*, is the representation of two series of ribs, *f*, running from said series *b* vertically upward to the top, leaving plain spaces. On the surface at the bottom, extending from the 40 series *e* to the lower edge, is the representation of two series of ribs, *g*, leaving a plain space on the surface, as shown in the accompanying illustration.

I claim—

The design for the hip-section of a corset, 45 consisting of the representation of transverse series of ribs *a b c*, with the series of ribs *d* running diagonally from the series *b* downward and forward to the series *a*, and a series 50 of ribs, *e*, running diagonally downward from the series *a* to the series *e*, leaving a plain space at the front and rear, with the vertical series of ribs *f* at the top and *g* at the bottom, leaving plain spaces on the surface, as 55 shown in the accompanying illustration.

ISAAC STROUSE.
